Assistant Examiner — Kayla Marie Bennett(74) *Attorney, Agent, or Firm* — Jose Cherson Weissbrot(57) **CLAIM**

The ornamental design for a fastening strip, as shown and described.

DESCRIPTION

FIG. 1 is a front perspective view of a fastening strip showing my new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is a partial enlarged view of FIG. 1.

The dot-dash-dot broken lines in the drawings depict boundaries of enlargement that form no part of the claimed design.

1 Claim, 8 Drawing Sheets(56)
